LIGHTING UNIT

Abner Fleetwood Henry Davis, Los Angeles,
Calif., assignor to Faries Manufacturing Com-
pany, Decatur, Ill., a corporation of Illinois

Application December 10, 1936, Serial No. 115,116

6 Claims. (Cl. 240—81)

My invention has for its principal object to provide a lighting unit which will spray the light rays, emitted by a source of light such as an electric bulb, over a fan-shaped area on a desk 5 or table with a high degree of efficiency.

A further object is to provide a construction which will shield the light source entirely from the eye of a person seated at a desk or table, while at the same time, redirecting the light rays 10 over the said fan-shaped area in a highly efficient manner.

A further object is to provide one or more supplemental and redirecting reflectors where a greater degree of intensity is desired.

15 My means of accomplishing the foregoing objects may be more fully comprehended by having reference to the accompanying drawings, which are hereunto annexed and are a part of this specification in which:

20 Fig. 1 is a side view of my invention applied to a portable or table lamp, portions of the structure being shown in section;

Fig. 2 is a fragmentary detail view showing the manner of supporting an auxiliary reflector;

25 Fig. 3 is a view similar to Fig. 1 showing different forms of supplemental reflectors.

Fig. 4 is a top plan view of Fig. 1 showing diagrammatically the contour of the light rays as they strike the top of a desk.

30 Similar reference numerals refer to similar parts throughout the entire specification.

For the purpose of illustration, I have shown my invention in connection with a portable or table lamp, but this is solely to show a concrete embodiment of my invention, for I do not wish to be understood as limiting myself in any particular to the specific structures shown and described, for many changes may be made in the application and use of my invention regardless of the manner in which the light source is supported.

35 As shown in the drawings, a light source 1 is mounted in a socket 2 carried by a tube 3 through which the electric conductors (not shown) may be carried to the socket in the usual manner. The socket is enclosed in a cylindrical casing or pedestal 4 which is mounted upon a base 5 in the interior of which is a metal weight 6 which operates to maintain the lamp in proper 40 position. The weight is held in place by means of a nut 7 mounted upon the lower end of the tube 3.

The casing 4 is flared outwardly adjacent the skirt of the lamp 1 as at 8. Inside of the flared 45 portion 8 of the casing 4, I may provide a sup-

plemental reflector 9 which receives the light rays from the source and directs them upwardly so that they will impinge upon a reflecting surface of a concave reflector member 10, of larger diameter than the reflector 9, the center of the 5 concave member 10 being eccentric to the center of the light source. The reflector 10 is carried by a reflector tube 11 which extends around its exterior as clearly seen in Fig. 1, its lower end being secured in position to 10 the casing 4. This supplemental reflector 9 is held in place by means of a stud 12 mounted in the end 13 of the reflector tube 11, a nut 14 serving to hold the supplemental reflector 9 firmly in position.

15 As clearly shown in the drawings, reflector 10 is a surface of revolution generated about its axis, said axis being parallel to the axis of the smaller reflector and falling outside said reflector. It is obvious however that the surface of the reflector 20 may be somewhat modified to give it a more ornamental appearance without departing from the spirit of the invention.

Ventilating openings 15 and 16 are provided in the casing 4, as shown, they are two in number 25 though it should be perfectly obvious that any number requisite to provide perfect ventilation may be employed. A similar vent 17 is formed adjacent the lower end of the reflector tube 11.

It will be apparent from the foregoing description 30 that the direct rays emitted upwardly from the source will strike the concave reflecting surface of the member 10 whence they will be reflected, and redirected as clearly indicated by the arrows shown in the drawings. The other rays emitted by the source will impinge upon the supplemental reflector 9 from which they will be reflected onto the reflecting surface of the concave reflector member 10 where they will be 35 re-reflected and redirected as indicated by the 40 arrows.

The result of this construction is that the light rays as clearly shown by the arrows in Fig. 4, are spread out upon the desk or table 29 over a fan-shaped area in the front of the lamp and by 45 making the reflecting surface of the concave reflector 10 and of the supplemental reflector 9 of the most efficient quality, a very high degree of efficiency is attained and a very satisfactory illumination of the fan-shaped area in front of 50 the lamp follows.

It may, in some cases, be found desirable to furnish a redirecting reflector 18. In the drawings I have shown such a reflector 18 secured to two arms 19 and 20 of a U-shaped member, 55

the connecting portion 21 of which is attached to the casing 4 by means of rivets 22, or in any suitable or convenient manner. Where this additional redirecting reflector 18 is employed, the reflected light rays from the forward portion of the concave reflector 10 will impinge upon the reflecting surface of the redirecting reflector 18, as clearly indicated by the arrows in the drawings, which will redirect them to the table or desk in front of the lighting unit. The lighting unit will operate without the redirecting reflector 18, but as stated, it may also in some instances be found desirable.

In Fig. 3, I have shown a construction in which the auxiliary reflector 9 is omitted. This may be replaced by a supplemental reflector 23 supported by a coil spring 24 which is coiled around the skirt of the lamp or the reflecting surface may be on the lamp bulb itself or the reflector 23 may be entirely omitted and the inner surface 25 of the flared portion 8 may be provided with a coating of suitable reflecting material.

It may, in some instances, be found desirable to provide a separate reflector 26 mounted inside 25 of the concave member 10. When this is done, obviously the concave member 10 will not have its inner surface coated with reflecting material. This construction has the added feature, of providing for a space intermediate the concave member 10 and the reflector 26 which can be utilized 30 for ventilating purposes which will aid in keeping the concave member 10 cool.

It will be apparent from the foregoing description, that owing to the fact that the perimeter 27 of the concave reflecting member 10 extends below the upper edge 28 of the flared portion 8 of the casing 4 that it is impossible for any direct rays of light to strike the eye of the observer or of a person seated at the desk, while 40 by mounting the concave reflector eccentric to the center of the light source, as clearly seen in the drawings, I am able to provide for the illumination of a fan-shaped area directly in front of the lamp. In this manner, I obtain a high 45 degree of eye comfort without a corresponding loss in lumens due to absorption in shields commonly employed for this purpose.

Having described my invention, what I regard as new and desire to secure by Letters Patent is:

50 1. A stand lamp comprising a pedestal, a light source at the top thereof, a reflector surrounding said light source to direct the light rays upwardly, an upper concave reflector separate from and of larger diameter than the first said reflector supported above the light source and smaller reflector so as to receive the upwardly directed light rays and project them fan-shaped at one side of the pedestal, said upper reflector being constructed substantially as a surface of revolution generated about its axis with said axis positioned substantially parallel to the axis of the smaller reflector and to one side thereof.

65 2. A stand lamp comprising a pedestal, a light source at the top thereof, a reflector surrounding said light source to direct the light rays upwardly, an upper concave reflector of larger diameter than the first said reflector supported above the light source and smaller reflector so as to receive the upwardly directed light rays and 70 project them fan-shaped at one side of the pedestal, said upper reflector being constructed sub-

stantially as a surface of revolution generated about its axis with said axis positioned substantially parallel to the axis of the smaller reflector and to one side thereof, said upper reflector having a lower edge extending below the upper edge of the smaller reflector. 5

3. A stand lamp comprising a pedestal, a light source at the top thereof, a reflector surrounding said light source to direct the light rays upwardly, an upper concave reflector of larger diameter than the first said reflector supported above the light source and smaller reflector so as to receive the upwardly directed light rays and project them fan-shaped at one side of the pedestal, said upper reflector being constructed substantially as a surface of revolution generated about its axis with said axis positioned substantially parallel to the axis of the smaller reflector and to one side thereof and a tube secured to the pedestal adjacent the smaller reflector to support the larger reflector, there being ventilating apertures in said pedestal and tube to cool said reflectors. 10

4. A stand lamp comprising a pedestal, a light source at the top thereof, a reflector surrounding said light source to direct the light rays upwardly, an upper concave reflector separate from and of larger diameter than the first said reflector supported above the light source and smaller reflector so as to receive the upwardly directed light rays and project them fan-shaped at one side of the pedestal, said upper reflector being constructed substantially as a surface of revolution generated about its axis with said axis positioned substantially parallel to the axis of the smaller reflector and to one side thereof, the eccentrically mounted peripheries of the two reflectors being substantially aligned at one point. 15

5. A stand lamp comprising a pedestal, a light source at the top thereof, a reflector surrounding said light source to direct the light rays upwardly, an upper concave reflector of larger diameter than the first said reflector supported above the light source and smaller reflector so as to receive the upwardly directed light rays and project them fan-shaped at one side of the pedestal, said upper reflector being constructed substantially as a surface of revolution generated about its axis with said axis positioned substantially parallel to the axis of the smaller reflector and to one side thereof, the eccentrically mounted peripheries of the two reflectors being substantially aligned at one point. 20

40

6. A stand lamp comprising a pedestal, a light source at the top thereof, a reflector surrounding said light source to direct the light rays upwardly, an upper concave reflector of larger diameter than the first said reflector supported above the light source and smaller reflector so as to receive the upwardly directed light rays and project them fan-shaped at one side of the pedestal, said upper reflector being constructed substantially as a surface of revolution generated about its axis with said axis positioned substantially parallel to the axis of the smaller reflector and to one side thereof, and a redirecting reflector secured to the pedestal below the smaller reflector to redirect reflected rays on to the illuminated area at one side of the pedestal. 45

50

7. A stand lamp comprising a pedestal casing, a socket mounted in said casing, a source of light in said socket, said casing having an upwardly and outwardly flaring reflector which surrounds said light source, a weighted base for said casing, a concave reflector mounted above said light source, the perimeter of which extends below the upper edge of the flaring reflector, the axis of said concave reflector being parallel to the axis of the flaring reflector and substantially outside thereof, a tube for supporting said concave reflector and secured to said casing, there being ventilating apertures in said tube and casing, and a redirecting reflector secured to the outside 60 of said casing below the flaring reflector. 55

65

8. A stand lamp comprising a pedestal casing, a socket mounted in said casing, a source of light in said socket, said casing having an upwardly and outwardly flaring reflector which surrounds said light source, a weighted base for said casing, a concave reflector mounted above said light source, the perimeter of which extends below the upper edge of the flaring reflector, the axis of said concave reflector being parallel to the axis of the flaring reflector and substantially outside thereof, a tube for supporting said concave reflector and secured to said casing, there being ventilating apertures in said tube and casing, and a redirecting reflector secured to the outside 65 of said casing below the flaring reflector. 70
